UNITED STATES PATENT OFFICE.

FREDERICK J. MUELLER AND MILTON C. FISHER, OF ROCK ISLAND, ILLINOIS.

FOOTBALL-GAME BULLETIN BOARD.

Application filed December 3, 1921, Serial No. 519,584. Renewed November 26, 1924.

To all whom it may concern:

Be it known that we, FREDERICK J. MUELLER and MILTON C. FISHER, citizens of the United States, residing at Rock Island, in the county of Rock Island and State of Illinois, have invented certain new and useful Improvements in a Football-Game Bulletin Board, of which the following is a specification.

10 Our invention relates to a bulletin board for foot-ball games, by the use of which there may be displayed the plays and movements of a regular game, in such a manner that they may be readily discerned by a considerable number of people in the vicinity of the board. By the use thereof games which are being played at a distance can be depicted play by play, for the edification of those who are interested in the progress and 20 outcome of the game.

One of the purposes of the invention is to provide a suitable board of sufficient size so that the plays which are being indicated thereon may be discerned by a multitude of 25 observers who are near the same, said board having displayed thereon the representation of a foot-ball field, and being provided on its face with a mechanically controlled object by means of which the usual movements 30 of a foot-ball may be indicated.

Another purpose of the device consists in the support of a pair of objects, one on each side of the board, in such a manner that the movement of one of such objects in any direction will be followed at once by a corresponding movement of the other of said objects, said means including automatic devices for holding said objects normally at a central or neutral position, and for returning 40 the same thereto when the fortunes of the game require it.

Another feature of the invention consists in the arrangement at each end of the board of series of openings capable of receiving 45 cards containing the names of the contesting teams and the names of the players thereon, in connection with which pockets are provided to receive small cards indicating the number of points made by each of such players, as the same are scored.

Another object of the invention is to provide the board with groups of display spaces, in which may be posted cards or plates showing various plays and conditions of the game, 55 such cards being positioned from the rear of the board, through openings therein. These

are preferably arranged at the end or ends of the board, but similar openings are provided on the main part of the board for showing other features and conditions of the game, as will hereinafter more fully appear.

Another purpose of the invention is to have the movement of the ball, and the disclosure of other circumstances pertaining thereto, carried on by operators in rear of the board, and entirely concealed thereby, adding greatly to the interest of the game, as viewed by those in front of the board.

In the drawings:

Fig. 1 shows the invention in front elevation.

Fig. 2 is a rear elevation thereof.

Fig. 3 is a top edge view of the device.

Fig. 4 shows a portion of the rear face of the invention, enlarged.

Fig. 5 is a cross-section of one of the drums 7.

Fig. 6 is a horizontal section through one of the pockets at the upper part of the board and the plates contained therein.

Similar parts of the device are indicated by corresponding reference characters throughout the several figures.

1 represents a base or platform, upon which is supported in a vertical position a board 2, upon the front face of which is portrayed a foot-ball field, or grid-iron, as indicated at 3. The board is intended to be supported at such a distance above the ground as to be conveniently read by those in the immediate vicinity thereof.

At the ends of the board 2 are mounted wings or extensions 4 and 5, in the same vertical plane with each other, but set a little in advance of such board, leaving narrow gaps between the ends of the board and the adjacent edges of the extensions. In the rear faces of said extensions, near the outer corners thereof, are rigidly secured shafts 6, upon which are rotatably mounted twin drums 7. Upon one set of said drums are wound the ends of cords 8, which extend to a point of intersection in front of the board 2, centrally of the field 3. Fixed to such cords at their point of intersection is a small object 9, easily discernible, and preferably in the form of a miniature foot-ball. By using a white object and giving to the field 3 a dark color the contrast will make the ball more easily distinguished.

Similar cords 10 are wound at their ends upon the rear set of drums, marked 7, for

distinction, such cords passing in rear of the board 2 to a central point thereof, where they are attached to a plate 11, from which projects rearwardly a handle 12. The rear face of the board 2 is likewise provided with the design of a foot-ball field, corresponding in size and position with the field 3 on the front of the board. This is shown at 13.

The drums 7 are each fitted with stored power devices, consisting, in the embodiment shown and described herein, of coiled springs 14, attached at one of their ends to said drums, and at their other ends to the shafts 6. (Fig. 5.) The tension of the springs in all of the drums is so adjusted that the object 9 on one side of the board and the handle 12 on the opposite side will be held normally at a central point. In other words, the springs at one end of the board counterbalance those at the other end. If the handle 12 is moved longitudinally of the board it will result in the unwinding of the cords 10 at that end, with an increase in the tension of the springs in the drums at that end, while at the other end of the board the cords 15 will be wound up, and the tension of the springs in the drums correspondingly diminished. As a consequence, if the handle 12 is released, it will be returned at once to a central position. In the same manner the handle 12 can be moved upwardly or downwardly, or in a diagonal direction, so that it is possible to move such handle to any part of the field, or beyond the boundaries of the 20 field at either end or at the sides.

It will be evident that the movement of the handle 12 will be accompanied by a corresponding movement of the object 9, and that if an operator at the rear of the board indicates with said handle the movement of a foot-ball on the field 13, the play will be duplicated on the field 3 by the ball 9. By this means if the operator is supplied with the necessary information in regard to the 25 progress of the game he can impart the same to the spectators in front of the board.

The wings 4 and 5 are each fitted with a series of openings 15 and 16, having guides at their edges to receive sets of cards, the upper cards 17 and 18 being intended to disclose the names of the contending teams, and the remaining cards 19 and 20 bearing the names of the various players thereof. Such cards are removably held in place so as to permit of the removal and replacement of the cards, as may be required. At the ends of the several openings are letters indicating the positions of the various players, and pockets 21 are provided at the inner ends of said openings in which may be placed small cards, as shown at 22, Fig. 1, to show the number of points made by a player.

By moving the name-card of one of the players a little out of position the fact can be communicated that such player is having a

part in the play that is being made, and similarly, by moving the card at the top of the column out of place it can be shown which side is in possession of the ball.

At the ends of the board are pairs of pockets 23, having openings or slits in their adjacent edges through which cards may be introduced into the space between such pockets, to indicate the number of "Yards lost" by a player, such designation appearing on the board just above the pockets. In the same way "Yards gained" and "Yards needed" can be indicated by means of cards in pockets 24 and 25, and the number of "Downs" can be shown at 26. This information relates to the actions of an individual player, and need be arranged at one end of the board only, if desired, or at a central point on said board.

At the bottom of the board 2 are small frames 27, representing the several quarters in which the game is played, in which may be inserted from the rear small cards indicating the number of scores for each quarter; also frames 28, in which may be disclosed the total scores of each team.

Extending vertically in rear of the players' names are metal straps 29, secured at top and bottom to the wings 4 and 5, and provided with lettering opposite the several names, showing the positions of the players, the same as on the front of the board. The rear faces of the name-cards can also have attached thereto small paper tabs, as shown at 30, by means of which such cards can be moved in the openings.

At the top of the board 2 is a series of pockets 31, 32, 33, 34 and 35, each containing a set of plates provided on their outer faces with designations of various movements of the balls and operations of the players. Each pocket is formed by striking out a portion of the material of the board, as shown at 36, and the space thus formed contains a number of plates 37, each provided with an ear 38 by means of which it may be manipulated. When it is desired to show what the play is, corresponding plate 37 is slipped to one side through the opening in the side of the pocket, so that the wording thereon will be disclosed above the field 3, as shown in Fig. 1. The various plays and circumstances are grouped in such a way as to permit the combination of two or more happenings connected with a single play of the ball. For instance, the plates contained in pocket 31 relate to the disposition of the ball, as whether a kick-off, drop-kick, etc., and on the rear face of the board are suitable markings in line with the several ears on the plates, so that the operator can readily tell which plate is to be moved.

In Fig. 1 three of the plates are shown exposed, indicating at 35 that an end run has just been made, and at 32 that it was made

round the right end. The plate at 33 shows that the player was tackled. The arrangement of the face of the board further indicates that the Independents have the ball, 5 that Johnson is the player who made the run, and that he was tackled by Bolan of the other team. It also appears at the right end of the board that there were sixteen yards gained, with two downs, and six yards 10 needed.

The marking on the front of either of the plates 37 is repeated on the back of the plate next in front thereof, (see Fig. 2) thus indicating to the operator that the 15 right plate has been exposed. When the second plate from the rear is moved outwardly it is accompanied by the first plate, which is concealed by it, and when it is desired to expose the plate farthest to the 20 front all of the other plates are necessarily moved therewith. The duplicate marking for this last plate is on the inner face of the pocket-plate 36. The name cards are also marked on their backs for the convenience 25 of the operator, as are the cards containing numbers.

The board 2 and its extensions are preferably formed of sheet-metal, provided with angle-plate frames on their rear faces.

30 The arrangement of the various designating cards and plates, as shown in the drawings herein, is for the purpose of illustration chiefly, and changes can be made in the location and manner of arrangement 35 thereof without departing from the general scope of the invention.

It is not essential that the drums 7 and 7^a shall be integrally formed, as the devices 40 for controlling the action of the ball 9 and handle 12 may be separate mechanisms. In the joint operation of the handle and ball, however, it is necessary that the drums be at least operatively connected. It will be evident that if the cords 10 were to be disconnected the ball 9 could still be manipulated 45 by an operator standing in front of the board. This would not be practical, however, as a large part of the board would be concealed by the body of the operator.

50 Two or more operators are essential to the successful working of the board, one of whom manipulates the handle 12, changing the position of the ball, and the other or others of whom are required to shift the various cards and plates. It will be obvious that this can all be accomplished from the rear of the board, with the operators concealed thereby, as hereinbefore mentioned.

60 What we claim, and desire to secure by Letters Patent, is:

1. In a device of the class described, a 65 vertically mounted board, provided on its front face with the diagram of a foot-ball field; a double system of spring-balanced

cords, on opposite sides of said board, so as to intersect at a central point of said board; an object attached to the cords in front of said board at the point of intersection thereof; and a guiding member attached to the cords in rear of said board, for the manipulation of the object in front thereof. 70

2. In a device of the class described, a vertically mounted board provided on its 75 opposite faces with diagrams of a foot-ball field, in register with each other; a system of spring-balanced cords on the front side of said board, intersecting at a central point thereon, and provided with an indicator at their point of intersection; and a secondary system of spring-balanced cords, operatively connected with said first-named system, connected at a central point on said board, in rear thereof; and a guiding member 80 attached to said last-named cords at the point of junction thereof, by means of which the indicator in front of the board may be manipulated. 85

3. In a device of the class described, a 90 vertically mounted board, provided on its opposite faces with diagrams of a foot-ball field, in register with each other; twin drums rotatably mounted at opposite corners of said board; two systems of cords on opposite sides of said board, operatively connected with said drums and uniting at a central point on said fields; an indicating object secured to the cords in front of said board, at said central point; a controlling 95 member attached to the cords in rear of said board, at said central point; and tension devices in said drums, tending to return said indicating object and controlling member to a central point whenever they are moved 100 therefrom. 105

4. In a device of the class described, a vertically mounted board, provided on its opposite faces with diagrams of a foot-ball field, in register with each other; twin 110 drums rotatably mounted at opposite corners of said board; cord suspension devices operatively connected with said drums on opposite sides of said board, and adapted to support a pair of objects in front of said fields; and stored power mechanism in said drums, holding said objects normally at a central point on said fields, the movement of said objects away from either of said drums tending to increase the tension of the 115 mechanism therein, and correspondingly decrease the tension of the mechanism in the drums toward which said objects move. 120

5. In a device of the class described, a vertically mounted board provided with a 125 diagram of a foot-ball field on its front face; twin drums rotatably mounted at the corners of said board; stored power devices in said drums controlling the action thereof; two sets of diametrically opposed 130

45
cords uniting said drums and capable of being alternately wound or unwound thereon; an indicating object carried by one set of cords in front of said board; and a controlling member connected with the other set of cords in rear of said board; the tension of said stored-power devices tending to hold said indicating object and controlling member normally at a central point on said board, the movement of said ele-

ments away from such central point operating to increase the tension of said stored power devices in one direction and correspondingly decrease the same in the opposite direction, with a tendency to keep the force of said devices always equalized. 15

In testimony whereof we affix our signature.

FREDERICK J. MUELLER.
MILTON C. FISHER.
